RESUSCITATOR

Le Roy G. Fox, Los Angeles, Calif., assignor to
Clarence N. Erickson, Glendale, Calif.

Application April 24, 1943, Serial No. 484,443

5 Claims. (Cl. 128—29)

This invention relates to artificial respiration apparatus or resuscitators wherein a gaseous fluid operated mechanism controlled by the lung capacity of the patient alternately directs gaseous fluid into and withdraws it from the patient's lungs to promote respiration and resuscitate the patient.

Heretofore in such resuscitators, the gas operated control mechanism has been directly supported by or mounted on a gas tank or other source of supply of gas under pressure or connected thereto by rigid fittings and mounted in a case or cabinet corresponding in size to a large suitcase or small trunk, with flexible hose lines for connecting the mechanism to a mask. In these machines the working mechanism includes diaphragm operated valves and a plurality of ports, passages and elements such that the machine constitutes a relatively large and heavy unit of considerable weight and bulk requiring the mounting thereof in a large case or cabinet and the direct connection of the gas tanks therewith, whereby the machine as a whole will be portable. Due to the construction and arrangement of such a machine it is not practicable and in many cases not possible to treat more than one patient at a time inasmuch as provision is made for the connection and operation of but one mask at a time per machine. Moreover, the weight, size and bulk of these machines make it difficult to transport them and serious delays are likely to occur in the application of the resuscitator to patients in field operations and in confined places and where access to the patient would be difficult with large and heavy equipment.

It is therefore an important object of my invention to provide a resuscitator wherein the gas operated mechanism is of such improved construction and arrangement that it is of minuscule proportions compared to resuscitation mechanisms heretofore used, and is actually smaller than the mask and supported thereby to form a complete unit subject to ready connection with a gas tank or other source of supply of gas under pressure by means of a single flexible hose line.

Another object of my invention is to provide a resuscitator such as described which may be more conveniently shipped, stored and carried from place to place as well as applied to a patient, and is constructed so that a plurality thereof may be connected with a single source of supply of gas for independent or simultaneous operation in a much more efficient and economical manner than possible where a plurality of independent re-

suscitator units of the type heretofore used are simultaneously operated.

Another object of my invention is to provide a resuscitator of the character described which is of such small and compact form that a plurality thereof may be carried in a cabinet or case of a size which would accommodate but one machine of the type heretofore used, with any one or all of the units subject to a convenient and efficient application in locations and under conditions where the type of machine heretofore used would be difficult, if not impossible, of use.

A further object of my invention is to provide a gas operated resuscitator mechanism which is smaller, more compact, of less weight, size and bulk, cheaper to manufacture and more economical and efficient in use than gas operated resuscitator mechanisms heretofore made, by reason of the use of a novel construction, arrangement and combination of comparatively few parts and elements including a housing having a gas chamber for communication with a mask, a Venturi tube carried by the housing with its suction port open to the chamber at all times and its discharge port subject to being opened to the atmosphere, a means for connecting the Venturi tube with a source of supply of gas, a diaphragm in the chamber, a valve for controlling the discharge port of the Venturi tube, and a means of operative connection between the valve and diaphragm for opening and closing the valve responsive to movement of the diaphragm so that when the valve is closed, gas under pressure will flow through the Venturi suction port, into the chamber for delivery to the mask and the lungs of the patient and when the valve is opened, said Venturi tube will evacuate the patient's lungs through the mask, chamber and open discharge port.

Another object of my invention is to provide a resuscitator of the character described having a valvular means mounted on the housing of the gas operated mechanism so as to be readily accessible and operable at will for rendering the mechanism inoperative as a resuscitator and operative as an insufflator or what is known in the art as an inhalator, and vice versa, this valvular means also serving as a safety valve which will open responsive to a fluid pressure beyond safe limits, for example, beyond approximately four ounces (13 mm. of hg.) during the inhalation phase of a resuscitation operation of the machine.

Yet another and important object of my invention is to provide a resuscitator of the character

described which is constructed so that it may be conveniently held with one hand in the properly applied position with all controls readily accessible to the operator and the weight and pressure of the unit against the patient's face under control of the operator.

An additional object of my invention is to provide a small, compact, gas operated working mechanism for a resuscitator which may be directly mounted on top of the mask or supported close thereto on rigid tubing with said tubing serving as a convenient handle and affording a controlled application of the mask whereby the correct pressure and contact of the mask against the patient's face is assured.

Another object of my invention is to provide a resuscitator working mechanism wherein a Venturi tube, a single pressure operated control valve and a toggle device operatively connecting the control valve with a diaphragm, are of such novel construction, relative arrangement and simplified design that the working mechanism as a whole consists of fewer parts, is less expensive to manufacture, smaller and more compact, lighter as to weight, and more reliable in operation than working mechanisms heretofore employed in resuscitators, and also subject to being mounted on a gas tank or other source of supply of operating fluid, or supported by and adjacent the mask or between the mask and source of supply of operating fluid and in all cases will constitute an improvement in the art.

Yet another object is to provide a resuscitator of the character described which is provided with an anti-contamination valve which may be opened to the atmosphere between the mask and working mechanism should the patient vomit or cough up sputum, thereby preventing contamination of the working mechanism.

Another object of my invention is to provide a resuscitator mechanism wherein an appreciable saving in strategic materials and a decided reduction in the size, weight and bulk of the mechanism as well as a considerable reduction of the number of parts employed and a more reliable performance are afforded by the use of a particular construction and relative arrangement of a Venturi tube and a control valve in which the valve is mounted in the tube and operated by a pressure responsive diaphragm so that when closed the Venturi tube will discharge gas under pressure for introduction through a mask into the lungs of a patient and when opened will cause the Venturi tube to operate for evacuating the lungs of the patient.

Another object of my invention is to provide a resuscitator of the character described which is designed to be operated from a tank of oxygen or similar gas under pressure, or by means of a simple manually operable air pump or other source of supply of air under pressure, and is particularly adapted for use and transportation in aircraft, submarines and other vehicles having limited space and facilities.

With the foregoing objects in view, together with such other objects and advantages as may subsequently appear, the invention resides in the parts and in the combination, construction and arrangement of the parts hereinafter described and claimed, and illustrated by way of example in the accompanying drawings, in which:

Fig. 1 is a side elevation of a resuscitator embodying my invention as connected to a source of supply of gas under pressure;

Fig. 2 is an enlarged horizontal sectional view taken on the line 2—2 of Fig. 1;

Fig. 3 is a vertical sectional view taken on the line 3—3 of Fig. 2; showing the control valve in open position as when evacuating the lungs of a patient;

Fig. 4 is a sectional view corresponding to Fig. 3 but showing the control valve in closed position as when introducing gas into the lungs of a patient;

Fig. 5 is a fragmentary side elevational view of a modified form of resuscitator embodying my invention;

Fig. 6 is an elevational view of another modified form of my invention;

Fig. 7 is an elevational view of a third modified form of this invention.

Referring to the drawings more specifically, it is seen that one embodiment of my invention generally includes a mask A for the most part made of transparent material and adapted to be applied over the nose and mouth of a patient, an enclosed working mechanism B supported by the mask and operable for introducing gas into and withdrawing it from the lungs of a patient responsive to the lung capacity of the patient, a single flexible hose line C, connecting the working mechanism with a source of supply D of gaseous fluid under pressure, a pressure regulator E, a pressure gage F and an intake valve G operable on the exterior of said working mechanism for controlling the flow of gaseous fluid thereto.

As shown in Fig. 1 the enclosed working mechanism B is disposed on top of the mask A and serves as handle for applying the mask and holding it in proper position on the face of the patient, said mechanism being of considerably smaller diameter than the mask and affording ready access to the gas supply valve G as well as making it possible for the operator to clearly see the patient's face through the transparent mask to note any reaction so that the mask or the mechanism may be quickly and properly manipulated or regulated to best suit the condition of the patient.

In accordance with my invention the working mechanism B is contained in a cylindrical housing 1 formed of telescopically joined sections 1a and 1b and provided with a cylindrical wall 2, an inner wall 3 and an outer wall 4, said housing being of considerably less diameter and of less height than the diameter and height of the mask for the purposes hereinbefore noted.

Removably screwed into the smaller section 1a of the housing 1 is an annular supporting member 5 for a diaphragm 6 and a Venturi tube assembly 7. The diaphragm 6 is held on a flange 8 on the supporting member 5, by means of a ring 9 adapted to be engaged with the outer wall 4 and the marginal portion of the diaphragm so as to be clamped against the diaphragm when the member 5 is screwed into the section 1a of the housing.

That portion of the housing 1 between the diaphragm 6 and the outer wall 4 constitutes an atmosphere chamber 10 open to the atmosphere by means of vents 11 formed at the base of a nipple 12 on the wall 4. This nipple is closed by a flanged plug 12', said nipple and plug preventing the vents from being closed or obstructed when the operator grasps the housing to apply the mask.

The inner end portion of the supporting member 5 has a close fit in the section 1b of the housing and supports the Venturi tube unit 7 between

the diaphragm and the inner wall 3, with said diaphragm exposed to the gas chamber 13 which is constituted in that part of the housing between the diaphragm and said inner wall. The Venturi tube assembly 1 as here provided consists of a Venturi tube 14 formed integral at its ends with the annular supporting member 5 and extending transversely thereof. The intake end of the Venturi tube 14 abuts the wall 2 of the housing and registers with an opening 15 in said wall so that a fitting 16 may be extended through said opening and screwed into said end of the tube for introducing gaseous fluid into the tube. The outer end of the fitting serves as a hose connection for the hose line C leading from the supply D of gaseous fluid. The intake valve G is mounted intermediate the ends of the fitting 16 and together with associated parts constitute a valved intake means for gaseous fluid under pressure.

The Venturi tube 14 has its outlet end in registration with a discharge port or opening 18 in said wall 2 of the housing. Threaded into the opening 18 is a muffler 17 comprising a small perforated casing 19 having felt or like porous muffler elements 20 therein between the apertures 21 thereof and the opening 18, to reduce the noise of the fluid as it discharges to the atmosphere. The fitting 16 in being screwed into the intake end of the Venturi tube 14 holds the tube in registration with the intake and discharge openings 15 and 18 respectively.

Screwed into the bore of the Venturi tube 14 is a tubular nozzle member 22 adapted to discharge a fluid jet through a tubular Venturi member 23 likewise screwed into said bore but disposed between the member 22 and the discharge end of the Venturi tube.

A "suction" port 24 is provided in the tube 14 for discharging fluid under pressure into the gas chamber 13 as well as for evacuating said chamber through the Venturi tube assembly to the atmosphere. The port 24 opens into an annular space 25 in the tube 14 formed between the reduced portion 26 of the nozzle member 22 and the wall of the bore of said tube. This annular space is communicated with the bore of the tubular nozzle member 22 by means of a transverse opening 27 in said nozzle member. In this connection it will be noted, as shown in Figs. 2 and 3, that the nozzle member 22 has one nozzle 28 arranged to discharge a jet of fluid across the transverse opening 27 into and through a conical nozzle 29 which latter discharges a jet of fluid into the conical constriction or mouth 30 of the Venturi member 23, thus forming in combination a species of jet pump. As shown in Fig. 3 the nozzle 28 is spaced somewhat from the mouth 30 to define a conical extension of the space 25. However, the nozzle member 22 may be axially adjusted to regulate the width or size of this extension or to cause the nozzle 28 to seat in the mouth 30 for regulating the suction action through the port 24.

A valve bore 31 extends transversely through the tube 14 between the discharge end of the Venturi member 23 and the discharge end of the tube 14 at which latter a discharge port 32 is provided in registration with the outlet opening 18 in the housing. A valve member 33 is slidably in the bore 31 to bring a transverse valve port 33' therein into and out of registration with the bore of the member 23 and discharge port 32.

When the valve member 33 is closed, as shown in Fig. 4, pressure fluid will be discharged from

the nozzle member 22, through the opening 27, space 25 (see Fig. 2) and port 24 into the gas chamber 13. When the valve member 33 is opened, as shown in Fig. 3, the pressure fluid 5 discharges through the Venturi tube discharge port 32, opening 18 and the muffler 17 to the atmosphere, thereby producing a suction action through the port 24 and evacuating the gas chamber.

10 A toggle device is provided for operating the control valve 33 responsive to movement of the diaphragm 6 and includes a pair of arms 34 fixed to the diaphragm and arranged to straddle the tube 14. These arms are pivoted as at 35 to a 15 pair of like toggle levers 36 at points between the ends of the toggle levers while certain corresponding ends of said levers are pivoted as at 37 to ears 38 on the tube 14. The other ends of the levers 36 are pivotally connected with one end of 20 a valve-connected toggle lever 39, by means of a pin 40 supported by and extended between the levers 36, with spacer sleeves 41 thereon to center the lever 39 as shown in Fig. 2. The lever 39 extends loosely through a slot 42 in the steam 43 25 of the valve 33, said slot being of sufficient length to permit of necessary movement of the lever 39 relative thereto as shown in Figs 3 and 4.

Retractile springs 44 are connected at their ends to pins 45 and 46 carried by the pair of levers 30 36 and the single lever 39 respectively to provide a quick action of the toggle device for opening 35 and closing the valve 33 as well as for holding the valve in opened and closed positions. As shown in Fig. 3 the levers 36 will engage the tube 35 14 to limit the movement of the toggle levers to a position in which the valve 33 is opened and held open, while Fig. 4 shows how the toggle movement is limited by means of hook members 47 when the toggle is operated to close the valve, 40 said hook members being fastened to the tube 14 and arranged to engage the pin 46 on the lever 39.

It is important to note that upon removing the fitting 16 the entire working mechanism may be 45 lifted out of the section 1b of the housing with the removal of the housing section 1a from section 1b. This arrangement makes for ease of 50 assembling and disassembling the unit as well as ready inspection and replacement and repair of parts thereof.

As best shown in Fig. 2, a suction or vacuum relief valve unit 48 is mounted on the exterior of the housing 1 and comprises a small valve casing 49 screwed into an opening 50 in the housing 55 wall 2 and provided with an inwardly opening 55 spring loaded disk check valve 51 normally closing a vent opening 52 and operating when a predetermined sub-atmospheric pressure is developed in the chamber 13 such as might injure the 60 patient (say beyond four ounces of vacuum) to open said chamber to the atmosphere.

A combined insufflator and pressure relief valve 54 is mounted on the housing 1 and includes a small valve casing 55 having a threaded nipple 56 screwed into an opening 57 in the wall 2 and affording communication between said casing and the gas chamber 13. A disk valve 58 is mounted in the casing 55 and is urged inwardly against a seat 59 therefor by a spring 60. The 70 force of this spring is controlled by turning a screw cap 61 on the casing 55. When the cap 61 is screwed in to its limit, the spring will be so tensioned that it will yield and allow the valve 58 to open and discharge gas to the atmosphere 75 through vents 62 in the casing 55 when a posi-

tive pressure beyond safe limits, for example beyond four ounces, is attained in the gas chamber 13, thereby preventing injury of the patient.

When the screw cap 61 is screwed out to its limit, the tension of the spring 60 is lessened to the extent that the valve 58 will open responsive to a positive pressure less than the positive pressure required to move the diaphragm and open the valve 32. Thus the valve 32 remains closed and a steady flow of gas passes from the Venturi suction port 24 into the chamber 13 for insufflation purposes, as will be hereinafter more fully described.

The inner wall 3 of the housing 1 is provided with an opening or port 63 affording communication of the gas chamber 13 in said housing with a mask such as the mask A shown in Fig. 1, it being noted that this mask has the customary pneumatic marginal cushion 64 thereon provided with a valved inflation stem 65.

As shown in Fig. 1 the opening 63 in the housing is directly connected with the interior of the mask by means of a short tubular fitting 66 bringing the working mechanism and the mask close together, the working mechanism being literally supported on top of the center of the mask. The fitting 66 extends through an opening 67 in the mask and has a flange 68 engaged with the outer surface of the mask while a nut 68' is screwed onto the inner end of the fitting within the mask to hold the fitting in place. The outer end of the fitting 66 has a tight frictional fit in a socket member 69 extended into the chamber 13 from the opening 67. This means of connection provides for detachably connecting the working mechanism B (housing) with the mask.

Instead of connecting the working mechanism B close to the mask A as shown in Fig. 1, I may, as shown in Fig. 5, connect said mechanism to the outer end of a horizontally disposed piece of rigid tubing or conduit 70 which is connected with the mask by means of a fitting 71 similar to the fitting 66 and adapted to extend into a socket 72 in the side of the tubing 70 near the closed end 73 thereof. The tube 70 serves as a convenient handle and permits the operator to regulate the weight and pressure of the unit against the face of the patient and affords good visibility of the face of the patient through the transparent body of the mask. This arrangement, disposing the working mechanism to one side of the mask may be preferable in some instances to the "overhead" arrangement of Fig. 1. It affords ready access to the valves on the housing and it is seen that aside from the manner of mounting the working mechanism on the mask the construction and operation of this modified unit is the same as that of the form of my invention shown in Figs. 1 to 4 inclusive.

I may employ, as shown in Fig. 5, an anti-contamination butterfly type of valve 75 for controlling a vent opening 76 in the tubing 70. A spring 77 normally holds the valve in position closing the opening 76. Should the patient commence to vomit or cough up sputum, the operator by manipulating the lever 78 may move the valve to position shutting off the passage through the tube 70 to the working mechanism and opening the vent 76 so that foreign matter may be discharged through said opening and does not reach and contaminate the working mechanism.

Another modified form of my invention as shown in Fig. 6 is identical with that form of

the invention shown in Figs. 1 to 4 inclusive except that a rigid upright tube 80 is employed to connect the working mechanism B with the mask A and is of such length as to constitute a handle. The tube 80 may be provided with an anti-contamination valve 81 identical with the one shown in Fig. 5. In all other respects this form of my invention is identical as to construction and mode of operation with the device 10 shown in Figs. 1 to 4 and the identical parts shown are designated by the same reference characters as employed in Figs. 1 to 4.

The vertical handle provided by the tube 80 disposes the controls on the working mechanism 15 within convenient reach of the operator, affords a ready application of the mask and an effective control of the weight and pressure of the mask on the face of the patient also makes for greater visibility of the mask covered portions of the 20 patient's face.

Another modified form of the invention as shown in Fig. 7 takes into consideration the same mounting of the mechanism B on the mask A as shown in Fig. 1 but provides a rigid horizontal tube 82 as a connection between the fitting 16 and the hose line, whereby a handle is afforded on one side of the mask and working mechanism.

In all forms of the invention as here shown 30 the working mechanism B is of the same construction and follows the same mode of operation.

When a resuscitation operation is desired the screw cap 61 is screwed in to its limit to set the 35 valve 58 to operate as a safety valve. Upon now opening the intake valve G, fluid pressure will flow into the Venturi tube 14 and with the control valve 33 closed the diaphragm 6 bowed inwardly as shown in Fig. 4, the pressure fluid 40 will pass out through the Venturi port 24 into the chamber 10 and thence to mask A and into the lungs of the patient. When the pressure in the patient's lungs and in the chamber 13 reaches approximately four ounces, the diaphragm 6 will 45 be bowed outward so that the toggle levers 36 and 39 will be moved to open and hold open the control valve 33 as shown in Fig. 3, whereupon the exhalation cycle of the machine takes place 50 inasmuch as the Venturi tube 14 is then open to atmosphere through the valve 33 and operates to evacuate the lungs of the patient through the mask, chamber 13 and Venturi tube port 24 and Venturi tube 14. When a negative pressure of say 55 approximately four ounces is produced by the Venturi tube in the chamber 13 and patient's lungs, the diaphragm 6 will respond to atmospheric pressure in chamber 10 and be bowed inwardly into position shown in Fig. 4, whereby the valve 33 will again be closed and gas under pressure 60 will flow into the patient's lungs. These "inhalation" and "exhalation" cycles are repeated and controlled by the lung capacity of the patient and the rate of the resuscitation operation may be regulated by adjusting the intake valve G 65 which is readily accessible to the operator in all forms of the invention.

When the machine is to operate as an insufflator the operator unscrews the cap 61 and reduces the tension on the spring 60 to the point 70 that the valve 58 will open the chamber 13 to the atmosphere responsive to a pressure below that required to open the valve 33. With the valve 33 maintained in closed position a steady flow of oxygen passes from the Venturi tube 14 through 75 the port 24 into the chamber 13 and thence to

the patient. When the patient exhales the valve 58 will open and allow the exhaled gas to pass to the atmosphere. When the patient inhales the valve 58 will be closed whereby gas will flow to the patient. During this insufflation operation the flow to Venturi tube may be reduced as desired by regulating the intake valve G.

It is important to note that the housing and working mechanism therein are of minuscule proportions compared to housings and working mechanisms as heretofore employed and that the working mechanism itself consists of fewer parts and is much more simple as to construction and operation than any resuscitation mechanism heretofore produced and at the same time is reliable in performance and subject to a nicety of control, wherefore the objects and advantages of my invention as hereinbefore set forth are achieved in a particularly efficacious manner.

It is also important to note that my improved resuscitator is particularly well suited for use in aircraft operating in the substratosphere in that the machine may be operated as an insufflator to take the place of the oxygen mask as now used in airplanes, and when extremely high altitudes are reached and respiration of the occupants of the airplane becomes difficult it only being necessary to make a simple adjustment of the insufflator-safety valve to render the machine operable as a resuscitator and thereby promote normal or satisfactory breathing. The practicability of this use of my resuscitator is readily seen in consideration of its small size, lightness in weight, convenience of application, the provision for the operation of a plurality of the units from a single source of supply of oxygen or other suitable gaseous fluid, and in view of the selective operation of the machine as an insufflator and a resuscitator while the mask is applied to the user.

While I have shown and described specific embodiments of my invention I do not limit myself to the exact details of construction set forth, and the invention embraces such changes, modifications and equivalents of the parts and their formation and arrangement as come within the purview of the appended claims.

I claim:

1. A resuscitator comprising, in combination, a housing defining a gas-receiving chamber, said housing being provided with a port adapted for connection with a mask, conduit means traversing said chamber, said conduit means being fitted at one end for attachment to a source of gas under pressure and the other end thereof defining a discharge port open to the outer atmosphere, jet pump means mounted within said conduit and comprising a nozzle and constriction, valve means positioned between said constriction and said discharge port for opening and closing said discharge port, means responsive to changes in pressure within said chamber for operating said valve means, and port means in the side of said conduit communicating with said chamber, said port means being positioned at a point between said nozzle and said constriction so that suction is created therethrough when said valve means is open, said port means introducing gas from said conduit into said chamber when said valve means is closed and withdrawing gas from said chamber into said conduit when said valve means is open.

2. A resuscitator comprising, in combination, a housing defining a gas-receiving chamber, said housing being provided with a port adapted for

connection with a mask and a second port communicating with the atmosphere, diaphragm means separating said chamber from said second-named port, conduit means traversing said housing and chamber, said conduit means being fitted at one end for attachment to a source of gas under pressure and the other end thereof defining a discharge port open to the outer atmosphere, jet pump means mounted within said conduit, and comprising a nozzle and constriction, valve means positioned between said constriction and said discharge port for opening and closing said discharge port, means mounted within said housing for controlling said valve means, said last-named means being operated by said diaphragm in response to changes in pressure within said chamber, and port means in the side of said conduit communicating with said chamber, said port means being positioned at a point between said nozzle and said constriction so that suction is created therethrough when said valve means is open, said port means introducing gas from said conduit into said chamber when said valve means is closed and withdrawing gas from said chamber into said conduit when said valve means is open.

3. A resuscitator comprising, in combination, a housing defining a gas-receiving chamber, said housing being provided with a port adapted for connection with a mask and a second port communicating with the atmosphere, diaphragm means separating said chamber from said second-named port, conduit means traversing said housing and chamber, said conduit means being fitted at one end for attachment to a source of gas under pressure and the other end thereof defining a discharge port open to the outer atmosphere, jet pump means mounted within said conduit and comprising a nozzle and a constriction, valve means slidably mounted in said conduit adjacent said discharge port for opening and closing said discharge port, toggle means mounted within said housing for controlling said valve means, said toggle means being operated by said diaphragm in response to changes in pressure within said chamber, and port means in the side of said conduit communicating with said chamber, said port means being positioned at a point between said nozzle and said constriction so that suction is created therethrough when said valve means is open, said port means introducing gas from said conduit into said chamber when said valve means is closed and withdrawing gas from said chamber into said conduit when said valve means is open.

4. A resuscitator comprising, in combination, a housing defining a gas-receiving chamber, said housing being provided with a port adapted for connection with a mask, conduit means traversing said chamber, said conduit means being fitted at one end for attachment to a source of gas under pressure and the other end thereof defining a discharge port open to the outer atmosphere, jet pump means mounted within said conduit and comprising a nozzle and constriction, valve means positioned between said constriction and said discharge port for opening and closing said discharge port, means responsive to changes in pressure within said chamber for operating said valve means, port means in the side of said conduit communicating with said chamber, said port means being positioned at a point between said nozzle and said constriction so that suction is created therethrough when said valve means is open, said port means introducing gas

from said conduit into said chamber when said valve means is closed and withdrawing gas from said chamber into said conduit when said valve means is open, means providing a further port in said housing between said gas receiving chamber and the atmosphere, and valve means controlling said port for converting said resuscitator to use as an insufflator.

5. A resuscitator comprising, in combination, a housing defining a gas-receiving chamber, said housing being provided with a port adapted for connection with a mask and a second port communicating with the atmosphere, diaphragm means separating said chamber from said second-named port, conduit means traversing said housing and chamber, said conduit means being fitted at one end for attachment to a source of gas under pressure and the other end thereof defining a discharge port open to the outer atmosphere, jet pump means mounted within said conduit and comprising a nozzle and a constriction, valve means positioned between said constriction and said discharge port for opening and closing said discharge port, means mounted within said housing for controlling said

valve means, said last-named means being operated by said diaphragm in response to changes in pressure within said chamber, port means in the side of said conduit communicating with said chamber, said port means being positioned at a point between said nozzle and said constriction so that suction is created therethrough when said valve means is open, said port means introducing gas from said conduit into said chamber when said valve means is closed and withdrawing gas from said chamber into said conduit when said valve means is open, means providing a further port in said housing between said gas receiving chamber and the atmosphere, valve means controlling said port, spring means urging said valve means to closed position, and manually operated means for controlling the pressure of said spring between a predetermined maximum and a predetermined minimum, said minimum being less than the pressure necessary to cause said diaphragm to open said first-named valve means, said maximum being substantially equal to the limit of safe pressure within said chamber in excess of atmospheric pressure.

LE ROY G. FOX.
